Application March 13, 1943, Serial No. 479,048

8 Claims. (Cl. 18—17)

This invention relates to pads and in particular to cushioning pads for use in high pressure molding presses.

In the molding of resinous products, and particularly laminated resinous products formed of fibrous sheet material impregnated with synthetic resins, it has been necessary to back the pressing plates with pads in order to effect an equalization of the applied pressure. As disclosed in Patent No. 1,942,251, issued January 2, 1934, to G. H. Mains, and assigned to the assignee of this invention, one method utilized in obtaining the equalization of pressure was to employ pads constructed of layers of cloth and asbestos between the heating platens and the movable and head castings of the press. Generally pads of cellulosic material such as paper or cloth are thus used by the trade.

It has been found, however, that where the pads of the cellulosic material are used, because of the poor thermal conductivity of the cellulosic material a considerable loss in time and power is encountered in bringing the molding plates up to the molding temperature. Further, the pads have a relatively short life since the cellulosic material employed in making the pads fail in a relatively short period of time under the molding temperatures to which they are subjected during the molding cycle. This short life of the pads makes it necessary to interrupt the molding cycle to change pads with an accompanying loss of time in the operation of the press.

It is an object of this invention to provide a resilient pad having good thermal conducting characteristics for use in molding presses.

Another object of this invention is to provide an all metallic resilient pad that is substantially unaffected by molding temperatures and pressures encountered in molding presses in the molding of resinous products.

Other objects of this invention will become apparent from the following description when taken in conjunction with the accompanying drawing in which:

Figure 1 is a view, partly in section, of a fragment of a molding press embodying the teachings of this invention.

Fig. 2 is an enlarged plan view of the resilient pad utilized in the molding press of Fig. 1.

Fig. 3 is a view in section of the resilient pad taken along the line III—III of Fig. 2.

Fig. 4 is a plan view greatly enlarged of a fragment of the fibrous material employed in the pad of Fig. 3, and

Fig. 5 is another view of a fragment of the fibrous material taken along the line V—V of Fig. 4.

Referring to Fig. 1 of the drawing, a portion of a hydraulic press 10 is shown as having a stationary block or head casting 12 and a lower movable block or casting 14. The head casting 12 is supported by standards or posts 16 which extend from the main frame (not shown) which is suitably secured to a foundation. The movable casting 14 is disposed to be moved upwardly towards the casting 12 by a force applied to its lower surface as by rams (not shown) which are hydraulically operated.

15 Heating and cooling platens 18 and 20 are associated with the castings 12 and 14, respectively, being separated therefrom by pads 22 and 24, respectively, of asbestos or other material which is resistant to heat and which is a poor heat conductor. The platen 18 and associated pad 22 are secured to the casting 12 by the bolts 26 and the platen 20 and associated pad 24 are secured to the casting 14 by the bolts 28. Each of the platens 18 and 20 is provided with pipes 30 through which a suitable heating medium, such as steam, and a cooling medium, such as water, may be selectively circulated. The pads 22 and 24 function to retard the transfer of heat from the platens to the castings.

25 In accordance with this invention, when the heating and cooling platens 18 and 20 are separated by lowering the casting 14, a pad 32 is positioned adjacent to and substantially covering the surface of the platen 20. The pad 32 is a thin, flat, tubular member or envelope formed of resilient metallic material as will be described hereinafter, which functions to equalize the pressure applied without detrimentally retarding the flow of heat.

30 As illustrated, a stack formed of an alternate assembly of pressing plates 34 and molding material 36, such as laminated fibrous material impregnated with a synthetic resin, are then disposed on the pad 32, the alternate assembly terminating with a pressing plate 34. Another pad 32 is disposed between the top pressing plate 34 and the upper heating platen 18 to effect an equalization of the pressure applied to the pressing plates.

35 Referring to Figs. 2 and 3, the resilient pad members 32 are better illustrated. As shown, the pads are provided with large substantially flat surfaces 37 and 38 which are of a size substantially equal to the area of the pressing plates 34

with which the pads are to be associated. Each of the pads 32 is preferably formed of two substantially thin rectangular dish-shaped metallic members 40 and 42 having relatively shallow rims 44 and 46 respectively which, when the members are disposed to face each other, will match, whereby when the rims are seated the flat surfaces 37 and 38 are spaced apart and substantially parallel. The metallic members 40 and 42 of the pads 32 may be of any suitable resilient metal such as hot or cold rolled sheet steel or brass, or of thin spring steel. Preferably the sheet stock used in making the members 40 and 42 has a thickness of between $\frac{1}{64}$ inch and $\frac{3}{64}$ inch.

As shown, the space between the substantially flat sides 37 and 38 of the metallic members 40 and 42 forming the envelope 32 is filled with a pad 48 of a resilient fibrous material. Preferably the fibrous material 48 utilized in forming the filler is of steel wool, it being found that the relatively hard but springy fibers of steel wool gives an unusually long life to the resulting composite pad when subjected to the temperatures and pressures employed in the molding of resinous products. The steel wool may be in any form suitable for filling the space within the metallic envelope of the pad 32, such as in the form of a mat having any predetermined density, thickness and width depending upon the requirements, the mat having been formed by any suitable method such as by felting. Since the mats of steel wool do not always have uniformity, it is preferred to employ quilted layers of the steel wool as the filler for the envelope of the pad 32.

Referring to Figs. 4 and 5, there is illustrated the steel wool fibers 50 formed into a quilted pad 48 for use in the metallic envelope. These pads can be formed by laying the fibers of the steel wool substantially parallel, then quilting or retaining them in the substantially parallel relation as by means of weaving fine wires 52 across the pad substantially perpendicular to the direction of the steel wool fibers. The threads 52 of wire are preferably spaced apart. Where pads of the steel wool of this type are utilized, the filler may be formed of a plurality of the quilted pads, as illustrated in Fig. 5, one layer being superposed upon the other until a predetermined thickness sufficient for filling the metallic envelope is constructed.

Regardless of the manner in which the fibrous material is formed, after the metallic envelope is filled and the rims of the dish-shaped members are seated one on the other, the meeting edges of the metallic members are welded as shown in Fig. 3 at 54. Preferably the envelope is so filled with the fibrous material as to prevent excessive sideways movement of the fibrous material after the meeting edges of the metallic members are welded. In this form the sealed metallic pad 32 may be likened unto a free edge supported diaphragm being capable of movement similar to such a diaphragm.

With the pads 32 and the alternate assembly of pressing plates 34 and impregnated fibrous material 36 assembled and in position as described hereinbefore, the press is operated through its molding cycle, heat and pressure being applied to cure the molding material between the pressing plates 34. As pressure is applied to the mold elements, the pads 32 function to cushion and to equalize the pressure applied throughout the surface area of the molding plates. In addition to equalizing the pressure, since the pads 32 are of all

metallic construction and have a good thermal conductivity, the pads function to prevent local hot spots on the molding or pressing plates, efficiently distributing the applied heat over the entire surface of the pressing plates. As the press is operated to separate the mold elements, the pads 32 are so resilient as to return to their original shape.

The sealed metallic pads of this invention have an extremely long life as compared to the pads of cellulosic material employed heretofore, it being found that they have a life in excess of thirty times that of the pads of the cellulosic material. Further, because of the materials employed, the pads have a high mechanical strength and high endurance against fatigue for withstanding the pressures of up to 2000 pounds per square inch which are utilized in the molding operations. The metallic pads will not deteriorate or lose strength or resiliency under the high temperatures in the neighborhood of 200° C. to which they are subjected during the molding cycles. In addition, since the pads are sealed, there is no danger of contaminating the molded plate. It has been especially noted that because of the good thermal conductivity of the pad that time for heating the mold to molding temperature is reduced to three-quarters of the time necessary where pads of the cellulosic material employed heretofore are utilized.

Although this invention has been described with reference to a particular embodiment thereof, it is, of course, not to be limited thereto except insofar as is necessitated by the scope of the appended claims.

We claim as our invention:

1. A pad for use in a high pressure molding press comprising, in combination, a non-porous, resilient metallic envelope having spaced flat side walls of sheet metal having a thickness of between $\frac{1}{64}$ and $\frac{3}{64}$ inch, and a fibrous metallic material disposed between the spaced side walls to substantially fill the envelope.

2. A pad for use in a high pressure molding press comprising, in combination, a sealed metallic, non-porous and resilient envelope having spaced flat side walls of sheet metal having a thickness of between $\frac{1}{64}$ and $\frac{3}{64}$ inch, and a fibrous metallic material disposed between the spaced side walls to substantially fill the envelope.

3. A pad for use in a high pressure molding press, comprising, in combination, a thin flat non-porous tubular member of resilient metallic material having spaced side walls of sheet metal having a thickness of between $\frac{1}{64}$ and $\frac{3}{64}$ inch, and a resilient fibrous metallic material disposed between the side walls to substantially fill the tubular member.

4. A pad for use in a high pressure molding press comprising, in combination, a non-porous and resilient metallic envelope having spaced side walls of sheet metal having a thickness of between $\frac{1}{64}$ and $\frac{3}{64}$ inch, and a filler of steel wool disposed between the spaced side walls to substantially fill the envelope, the steel wool cooperating with the non-porous, resilient envelope to provide a thermally conducting, resilient pad.

5. A pad for use in a high pressure molding press comprising, in combination, a sealed envelope of non-porous resilient metallic material having spaced flat side walls of sheet metal having a thickness of between $\frac{1}{64}$ and $\frac{3}{64}$ inch, and a filler of steel wool disposed between the side walls to substantially fill the envelope and resiliently cushion the side walls, the steel wool and metallic

envelope cooperating to provide a resilient pad having good thermal conducting characteristics.

6. A pad for use in a high pressure molding press comprising, in combination, a pair of substantially thin, rectangular, dish-shaped, non-porous metallic members having substantially flat surfaces and relatively shallow rims, the metallic members being formed from sheet metal having a thickness of between $\frac{1}{4}$ and $\frac{3}{4}$ inch and being disposed with their rims seating against each other and their flat surfaces in spaced relation to form a thin flat resilient tubular member, resilient fibrous metallic material disposed between the flat surfaces to fill the tubular member, and a weld applied to the edges of the seated rims to seal the tubular member containing the resilient fibrous material, the filled and welded tubular member having a good thermal conductivity and being resilient.

7. A pad for use in a high pressure molding press, comprising, in combination, a sealed en-

velope of nonporous resilient metallic material having spaced side walls of sheet metal having a thickness of between $\frac{1}{4}$ and $\frac{3}{4}$ inch, and a filler consisting of a quilted pad of fibrous metallic material disposed between the side walls to substantially fill the envelope and resiliently cushion the side walls, the fibrous metallic material and metallic envelope co-operating to provide a resilient pad having good thermal conducting characteristics.

8. A pad for use in a high pressure molding press, comprising, in combination, a sealed non-porous tubular member of resilient metallic material having spaced flat side walls of sheet metal having a thickness of between $\frac{1}{4}$ and $\frac{3}{4}$ inch, and a resilient quilted pad of fibrous metallic material disposed between the side walls to substantially fill the tubular member.
